CLAIR L. FARRAND, OF SOUND BEACH, CONNECTICUT, ASSIGNOR OF ONE-THIRD TO
CORNELIUS D. EHRET, OF MOUNT AIRY, PHILADELPHIA, PENNSYLVANIA.

METHOD OF AND APPARATUS FOR THE RECEPTION OF RADIOSIGNALS.

Application filed October 18, 1919. Serial No. 330,488.

To all whom it may concern:

Be it known that I, CLAIR L. FARRAND, a citizen of the United States, residing at Sound Beach, Fairfield County, State of Connecticut, have invented a Method of and Apparatus for the Reception of Radiosignals, of which the following is a specification.

The object of this invention is to provide methods of and means for the reception of radio telegraphic signals, particularly signals of undamped waves.

My invention depends upon the discoveries, first, that the impedance of a high frequency circuit can be varied at a high frequency rate; second, that the amplitude of the signal current varies at a frequency equivalent to the difference between the frequency of the signal and the frequency of impedance variation when the frequency of resistance variation differs slightly from the frequency of the signal.

My invention, stated broadly, consists in the method of and apparatus for the periodic regulation of amplitude of the high frequency signal current, by means of a periodically changing impedance, whereby the regulation of amplitude corresponding in frequency to the difference in frequency between the frequency of the signal and the frequency of the impedance change is produced.

The following is a description of the method of and apparatus for attaining the above results, and will best be understood by referring to the accompanying drawings, wherein the same numerals refer to corresponding parts in all figures.

Fig. 1 shows diagrammatically the method of practicing my invention involving a means of regulating the impedance of a secondary circuit of a radio receiver; Fig. 2 shows diagrammatically the method of regulating the impedance of both primary and secondary circuits of a radio receiver; Fig. 3 shows diagrammatically the same method as Fig. 2, excepting that the impedance is varied for signal current when flowing in both directions; Fig. 4 shows diagrammatically the method involving the mechanical means of varying the coupling co-efficient between two

circuits of a high frequency inductor alternator in conjunction with a detector; Fig. 5 shows diagrammatically the method involving the same mechanical means as Fig. 4, utilizing the low frequency current component of the alternator to actuate the telephone.

Referring to Fig. 1, the numeral 1 is the antenna, 2 is the primary inductance, 3 is the earth connection, 4 is the secondary inductance, 5 is the secondary condenser, 6 is a detector herein shown of the Fleming valve type, of which 7 is the filament and 8 is the plate, and 10 is the filament heating battery; 9 is the telephone, all in combination forming a usual form of receiver. Across the terminals of the secondary condenser 5 are connected the filament 12 and plate 14 of a three-electrode vacuum valve 11. The grid 13 is interposed between plate 14 and filament 12, and a high frequency alternating potential is applied from source 17. With some types of valves it is advisable to include a negative potential battery 16 for the grid circuit. It will be understood by those skilled in the art that the resistance of the plate filament circuit of valve 11 is very high when the grid 13 is negative and will consequently increase the impedance of the receiver circuit 4—5 very slightly; however, as the grid 13 becomes more positive due to the alternation of the potential applied from source 17, the resistance of the plate filament circuit decreases, causing a corresponding decrease in the impedance of the receiver circuit and producing a corresponding reduction in the amplitude of the signal current flowing therein. Inasmuch as the impedance change of the receiver circuit is effected at high frequency rate differing slightly in frequency from the frequency of the signal, the signal current changes in amplitude periodically at a rate corresponding in frequency to the difference between the frequency of the signal and the frequency of the impedance change.

This periodically changing current, rectified, produces a low frequency current corresponding in frequency to the difference between the frequency of the signal and the frequency of the resistance change,

Referring to Fig. 2, the numerals show parts corresponding to Fig. 1. 18 is an inductance coupled to the primary and secondary circuits of the receiver and connected to the plate filament circuit of the three-electrode valve 11. In this manner the effective impedance of the primary and secondary circuits are changed, producing a signal corresponding in frequency to the difference in frequency between the frequency of the signal and the frequency of the impedance change.

Referring to Fig. 3, the numerals show parts corresponding to Figs. 1 and 2; 19 is a three-electrode vacuum valve comprising 20 the filament, 21 the grid, and 22 the plate, 23 the filament heating battery, and 24 the negative grid battery. The plate 14 of valve 11 and the filament 20 of valve 19 are connected to one terminal of inductance 18; the filament 12 of valve 11 and the plate 22 of valve 19 are connected to the other terminal of inductance 18; the sources of alternating potential 17 and 25 are connected to the grids of valve 11 and 19, respectively. These sources of alternating potential 17 and 25 are shown as alternators mounted on a common shaft, but may consist of any common form of oscillation generator. By the means shown in Fig. 3, the impedance of the receiver circuit is regulated for signal currents flowing in both directions. The reception efficiency of the arrangement shown in Fig. 3 is somewhat higher than that of the arrangement shown in Fig. 2.

Referring to Fig. 4, the numerals 26 represent the stator coils of a high frequency induction alternator connected to the secondary circuit of the receiver; 27 are the rotor coils of the alternator, connected by means of collector rings 28 and brushes 29 to the circuit consisting of inductance 30 and condenser 31; across the terminals of the condenser is connected a detector here shown as a Fleming valve 6; and telephone 9. Any suitable form of detector may be used. Due to the variation of coupling coefficient between circuit 4—5—26 and circuit 29—30—31 at a rate corresponding to the frequency of rotation of the alternator a signal is produced. The current in the detector circuit corresponds in frequency to the difference between the frequency of the signal and the frequency of rotation of the alternator. The alternator is shown having eight poles for clearness of illustration. It is assumed that a sufficient number of poles would be used to obtain synchronism with the signal at a reasonable speed. The inductor type alternator has advantages over the type shown at frequencies of the order of fifty thousand cycles per second.

Referring to Fig. 5, the numerals represent parts corresponding to Fig. 4. The rotor winding of the alternator is tuned by

means of inductance 32 and condenser 33 in series with telephone 9 to the difference in frequency between the frequency of the signal and the frequency of rotation of the alternator.

As the broad underlying principle herein disclosed is capable of various applications, such as frequency conversion at radio frequencies as well as at audible frequencies, it is not intended to limit the scope of the invention disclosed and claimed to the figures and apparatus shown and described, but to include therein the various modifications of apparatus and methods capable of periodically regulating the amplitude of the high frequency signal current, such as the periodic extraction of energy by resistance, the periodic change of capacitive reactance, the periodic change of inductive reactance, the periodic change of mutual capacitive or inductive reactance, or the periodic change of coupling coefficient. All of these may be classed generally under, and are intended to be understood as comprehended by, the phrase "the periodic change of impedance," as used in the method claims hereto appended.

Impedance variation at frequency different from the signal frequency and, more specifically, at audio frequency, is claimed in my prior application Serial No. 296,960, filed May 14, 1919.

Having thus described my invention, I claim:

1. The method of receiving and translating into a signal radio frequency signal-representing energy, which comprises receiving and detecting the signal-representing energy in a circuit whose impedance is always finite, independently varying the impedance of said circuit by varying an impedance between finite limits at a frequency above audibility, and translating the current as modified by said impedance variation into a signal.

2. The method of receiving and translating into a signal radio frequency signal-representing energy, which comprises receiving and detecting the signal-representing energy in a circuit whose impedance is always finite, independently varying the impedance of said circuit by varying an impedance between finite limits at a high frequency differing from the frequency of the signal-representing energy, and translating the current as modified by said impedance variation into a signal.

3. The method of receiving and translating into a signal radio frequency signal-representing energy, which comprises rectifying the radio frequency signal-representing energy in a circuit whose impedance is always finite, independently varying the impedance of said circuit by varying an impedance between finite limits at a frequency

- above audibility, and translating into a signal the rectified current as modified by said impedance variation.
4. The method of receiving and translating into a signal radio frequency signal-representing energy, which comprises rectifying the radio frequency signal-representing energy in a circuit whose impedance is always finite, independently varying the impedance of said circuit by varying an impedance between finite limits at a high frequency differing from the frequency of the signal-representing energy, and translating into a signal the rectified current as modified by said impedance variation. 70
5. The method of receiving and translating into a signal radio frequency signal-representing energy, which comprises impressing the received energy upon the anode-cathode circuit of a thermionic impedance, independently varying the impedance of said circuit by varying an impedance at a frequency above audibility, and translating into a signal the current in said circuit as modified by said impedance variation. 75
- 20
6. The method of receiving and translating into a signal radio frequency signal-representing energy, which comprises impressing the received energy upon the anode-cathode circuit of a thermionic impedance, independently varying the impedance of said circuit at a high frequency differing from the radio frequency of the signal-representing energy to impart to the current in said circuit an amplitude variation whose frequency is equal to the difference between said radio and high frequencies, and translating into a signal said amplitude variation of said current. 80
- 35
7. The method of receiving and translating into a signal radio frequency signal-representing energy, which comprises impressing the same upon a circuit including a thermionic impedance, independently varying the impedance of said circuit by varying a second thermionic impedance at a predetermined frequency, and translating into a signal the current as modified by said impedance variation. 85
- 40
8. The method of receiving and translating into a signal radio frequency signal-representing energy, which comprises impressing the same upon a circuit including a thermionic impedance, independently varying the impedance of said circuit by varying a second thermionic impedance at a frequency above audibility, and translating into a signal the current as modified by said impedance variation. 90
- 45
9. The method of receiving and translating into a signal radio frequency signal-representing energy, which comprises impressing the same upon a circuit including a thermionic impedance, independently varying the impedance of said circuit by varying a
- second thermionic impedance at a high frequency differing from the radio frequency of said signal-representing energy, and translating into a signal the current as modified by said impedance variation. 95
10. The method of receiving and translating into a signal radio frequency signal-representing energy, which comprises impressing the same upon a detector, independently varying the operation of said detector by a thermionic impedance varying in magnitude periodically at a frequency above audibility and translating into a signal the current as modified by said impedance variation. 100
11. The method of receiving and translating into a signal radio frequency signal-representing energy, which comprises impressing the same upon a thermionic detector, independently varying the operation of said detector by a thermionic impedance varying in magnitude periodically at a frequency above audibility, and translating into a signal the current as modified by said impedance variation. 105
12. The method of receiving and translating into a signal radio frequency signal-representing energy, which comprises impressing the same upon a detector, independently varying the operation of said detector by a thermionic impedance varying in magnitude periodically at a high frequency differing from the radio frequency of said signal-representing energy, and translating into a signal the current as modified by said impedance variation. 110
13. The method of receiving and translating into a signal radio frequency signal-representing energy, which comprises impressing the received energy upon a circuit with which is operatively related a thermionic device comprising an anode, cathode and control electrode, periodically varying the potential of said control electrode independently of the received energy at a frequency above audibility, and translating the resultant impedance variations into an audible signal. 115
14. The method of receiving and translating radio frequency energy, which comprises impressing the received energy upon a circuit with which is operatively related a thermionic device comprising an anode, cathode and control electrode, periodically varying the potential of said control electrode independently of the received energy at a frequency above audibility, and effecting current variation by the resultant impedance variations. 120
15. Receiving apparatus for translating radio frequency current comprising a rectifying detector, means for impressing the received energy thereon, a translating instrument controlled by said detector, means for independently varying the impedance, 125
- 130

- of the detector circuit comprising an associated thermionic impedance, and means for varying the magnitude of said thermionic impedance at a predetermined frequency.
16. Receiving apparatus for translating radio frequency current comprising a rectifying detector, means for impressing the received energy thereon, a translating instrument controlled by said detector, means for independently varying the impedance of the detector circuit comprising an associated thermionic impedance, and means for varying the magnitude of said thermionic impedance at a predetermined frequency above audibility.
17. Receiving apparatus for translating radio frequency current comprising a rectifying detector, means for impressing the received energy thereon, a translating instrument controlled by said detector, means for independently varying the impedance of the detector circuit comprising an associated thermionic impedance, and means for varying the magnitude of said thermionic impedance at a high frequency differing from the radio frequency of the received energy.
18. Receiving apparatus for translating radio frequency current comprising a detector circuit, and means associated therewith for effecting independent impedance variation comprising a thermionic device having an anode, cathode and field-producing means, and means for varying the field produced by said means at a predetermined frequency above audibility.
19. Receiving apparatus for translating radio frequency current comprising a detector circuit, and means associated therewith for effecting independent impedance variation comprising a thermionic device having an anode, cathode and field-producing means, and means for varying the field produced by said means at a high frequency differing from the radio frequency of the received energy.
20. Receiving apparatus for translating radio frequency current comprising a detector circuit, and means associated therewith for effecting independent impedance variation comprising a thermionic device having an anode, cathode and control electrode, and means for varying the potential of said control electrode at a frequency above audibility.
21. Receiving apparatus for translating radio frequency current comprising a detector circuit, and means associated therewith for effecting independent impedance variation comprising a thermionic device having an anode, cathode and control electrode, and means for varying the potential of said control electrode at a high frequency differing from the radio frequency of the received energy.
22. Receiving apparatus for translating radio frequency current comprising a detector circuit, and means associated therewith for effecting independent impedance variation comprising a path including a pair of thermionic devices in parallel with said path and each comprising an anode and a cathode, the anode-cathode paths of said thermionic devices being reversely related to said path, field-producing means for each of said thermionic devices, and means for varying the fields produced by said means at a predetermined frequency.
23. Receiving apparatus for translating radio frequency current comprising a detector circuit, and means associated therewith for effecting independent impedance variation comprising a path including a pair of thermionic devices in parallel with said path and each comprising an anode and a cathode, the anode-cathode paths of said thermionic devices being reversely related to said path, field-producing means for each of said thermionic devices, and means for varying the field produced by said means at a predetermined frequency above audibility.
24. Receiving apparatus for translating radio frequency current comprising a detector circuit, and means associated therewith for effecting independent impedance variation comprising a path including a pair of thermionic devices in parallel with said path and each comprising an anode and a cathode, the anode-cathode paths of said thermionic devices being reversely related to said path, field-producing means for each of said thermionic devices, and means for varying the fields produced by said means at a high frequency differing from the radio frequency of the received energy.
25. Receiving apparatus for translating radio frequency current comprising a detector circuit, a second circuit containing a thermionic impedance, a path traversed by the received energy, means for coupling said path to said circuits, and means for varying said thermionic impedance at a predetermined frequency.
26. Receiving apparatus for translating radio frequency current comprising a detector circuit, a second circuit containing a thermionic impedance, a path traversed by the received energy, means for coupling said path to said circuits and said circuits to each other, and means for varying said thermionic impedance at a predetermined frequency.
27. Receiving apparatus for translating radio frequency current comprising a detector circuit, a second circuit containing a thermionic impedance, a path traversed by the received energy, means for coupling said path to said circuits, and means for varying said thermionic impedance at a predetermined frequency above audibility.

28. Receiving apparatus for translating radio frequency current comprising a detector circuit, a second circuit containing a thermionic impedance, a path traversed by each other, and means for varying said thermionic impedance at a high frequency differing from the radio frequency of the received energy. 25
- 5 the received energy, means for coupling said path to said circuits and said circuits to each other, and means for varying said thermionic impedance at a predetermined frequency above audibility.
- 10 29. Receiving apparatus for translating radio frequency current comprising a detector circuit, a second circuit containing a thermionic impedance, a path traversed by the received energy, means for coupling said path to said circuits, and means for varying said thermionic impedance at a high frequency differing from the radio frequency of the received energy. 30
- 15 30. Receiving apparatus for translating radio frequency current comprising a detector circuit, a second circuit containing a thermionic impedance, a path traversed by the received energy, means for coupling said path to said circuits and said circuits to each other, and means for varying said thermionic impedance at a high frequency differing from the radio frequency of the received energy. 35
- 20

31. Receiving apparatus for translating radio frequency current comprising a circuit, a thermionic device operatively related to said circuit and comprising an anode, cathode and control electrode, means for periodically varying the potential of said control electrode at super-audible frequency independently of the received energy, and means controlled by the resultant current. 40

32. Receiving apparatus for translating radio frequency current comprising a circuit, a thermionic device operatively related to said circuit and comprising an anode, cathode and control electrode, means for periodically varying the potential of said control electrode independently of the received energy at a frequency above audibility, and means for translating the resultant current into an audible signal. 45

CLAIR L. FARRAND.
